US00D396032S

United States Patent [19]
Kondo et al.

[11] Patent Number: **Des. 396,032**
[45] Date of Patent: ****Jul. 14, 1998**

[54] **ELECTRONIC COMPUTER**

[75] Inventors: **Osamu Kondo**, Tokyo; **Masaaki Iino**, Saitama-ken, both of Japan

[73] Assignee: **Kabushiki Kaisha Toshiba**, Kawasaki, Japan

[**] Term: **14 Years**

[21] Appl. No.: **70,686**

[22] Filed: **May 13, 1997**

[57] CLAIM

The ornamental design for an electronic computer, as shown and described.

DESCRIPTION

FIG. 1 is a top, front and right side perspective view of an electronic computer showing my new design;
FIG. 2 is a front elevational view thereof;
FIG. 3 is a left side elevational view thereof;
FIG. 4 is a right side elevational view thereof;
FIG. 5 is a rear elevational view thereof;
FIG. 6 is a top plan view thereof;
FIG. 7 is a bottom plan view thereof;
FIG. 8 is a front elevational view thereof in a closed position;
FIG. 9 is a right side elevational view thereof in the closed position; and,
FIG. 10 is a top plan view thereof in the closed position. The structure shown in hatched lines is intended to depict environmental structure forming no part of claimed design.

1 Claim, 4 Drawing Sheets
